Charles F. Richards
BY
Cyrus K. Anderson
ATTORNEY

UNITED STATES PATENT OFFICE

CHARLES F. RICHARDS, OF WHITE HAVEN, PENNSYLVANIA, ASSIGNOR TO WILMOT ENGINEERING COMPANY, OF HAZLETON, PENNSYLVANIA, A CORPORATION OF PENNSYLVANIA

COAL-WASHING APPARATUS

Application filed November 2, 1927. Serial No. 230,427.

My invention relates to apparatus for washing coal for the purpose of separating therefrom impurities, which may consist of slate, "bony" material, stone or the like, and it has for its general object to provide an apparatus of novel but simple construction in which the washing and separating medium is supplied continuously and at substantially constant pressure.

It also is an object of the invention to provide means of novel construction for effecting a more thorough and complete separation of the impurities from the coal than heretofore has been practicable; and also to provide an improved construction of means for removing the impurities from the apparatus after their separation from the coal.

To these and other ends the invention comprehends the construction as hereinafter described in detail, particularly set forth in the claims and as illustrated in the drawing forming a part of this specification and to which reference should be made for a ready and clear understanding of the invention.

In the drawing:

Fig. 1 is a view in vertical central longitudinal section of an apparatus embodying the invention;

Fig. 2 is a view in elevation looking toward the right hand side of Fig. 1, a portion of the structure being shown in section; and

Fig. 3 is a top plan view of the structure shown in Figs. 1 and 2.

In the drawing I have shown a tank 1 provided with supporting feet 2 which are secured to and supported upon sills 3.

The tank 1 is of peculiar shape comprising a vertical wall 4 on what I shall term the front side thereof, which is the side from which the coal is discharged after having been washed and separated from the impurities of the character above indicated. The opposite or rear side of the tank is of curvilinear shape, as shown. The tank is provided with a vertically adjustable breast plate 5 connected with and adjustable by means of a rack bar 6 the teeth of which are in engagement with a gear 7 which is adapted to be rotated in either direction to adjust the said plate vertically either up or down.

The plate 5 is guided between the rear edge of a plate 10 and the front edge of a narrow plate 11, the latter having upon its rear edge a downwardly extending narrow flange 12. The plate 10 is connected at its opposite ends by means of rivets 13 to the opposite sides of the tank and is supported by the said rivets with the upper surface of its lower edge substantially flush with the lower edge of an opening 14 which extends horizontally in the vertical plate 4. The coal after it is washed or cleaned is discharged from the compartment 15 formed between the upper portion of the wall 4 and the upper portion of the adjustable breast plate 5. The plate 10 extends upwardly from the front plate 4 at an angle substantially as is shown in Fig. 1 of the drawing. The plate 11 is secured at its opposite ends by means of rivets 17 to the opposite sides of the tank 1, the said plate 11 being supported by the said sides.

The mixture of coal and impurities to be washed is discharged from a chute 20 into the upper rear corner portion of the tank 1 between the rear wall thereof and a pivotally supported baffle plate 21 which is suspended by means of arms 22 from a cross shaft 23 provided with an arm 24 having mounted thereon an adjustable weight 25. The action of gravity upon the arm 24 and the weight 25 is such as to hold the baffle plate 21 normally in position with its lower edge against a shoulder 26 formed in the transversely and downwardly extending plate 27 which constitutes the bottom of a compartment 30 within which the washing and separation of the coal from its impurities are effected. The plate 27 is bent so as to provide a plurality of portions angularly related to each other as indicated. Three of these portions, which I have designated respectively 31, 32 and 33, are provided with perforations 34. The portions 31 and 33 are inclined so that they form acute angles with vertical lines drawn therethrough and are located respectively in planes which are substantially parallel with each other. The upper edge of the portion 33 is connected with the lower edge of the portion 31 by means of the portion 32, the several portions being integral with each other. The

portion 32 extends upwardly and occupies a very nearly vertical plane.

The rear side of the tank 1 is curved, as previously stated, and cooperates at its lower end portion with a relatively narrow curved portion 37 to form a relatively narrow passageway 38 through which the water travels after it has been delivered thereto from a pipe, not shown, having connection with the short tubular projection 40. Located inside of the rear wall of the tank 1 I have provided a curved plate 41 the lower edge of which rests against the inner surface of the said rear wall, while the upper edge thereof contacts with the under side of the plate 27 at the upper edge of the portion 31, as shown in Fig. 1.

The water for washing the coal and separating impurities therefrom is delivered from a supply pipe, not shown, through the port or opening at 40 and thence through the narrow passage 38 within the tank 1 and thence upwardly through the perforations 34 in the portions 31, 32 and 33 of the plate 27. It will be observed that the upper portion of the curved plate 41 cooperates with the portions 31 and 32 of the plate 27 to form an elongated pocket and it will be apparent that the water which enters the said pocket under pressure, as it will be, is discharged not only through the perforations in the portion 31 but also through the perforations in the portion 32. The water also is discharged through the perforations in the portion 33. It will be noted, therefore, that water flows through the portion of the compartment 30 directly above or beyond the perforated portion of the plate 27 in what is in effect three streams, one stream emanating from the portion 31, another from the portion 32, and another from the portion 33. These three flowing portions or streams of water acting upon the material which has been delivered to the compartment 30 operate to cause ascending movement of the coal within said compartment but do not have sufficient force to cause a like movement of the slate or other impurities the specific gravity of which is greater than that of the coal.

The coal, which is caused to flow or move upwardly as indicated, is carried over the upper side of the narrow plate 11 and also over the upper edge of the adjustable breast plate 5. After having been carried over and beyond the breast plate 5 the coal falls or is deposited upon the upper side of the plate 10 along which it slides or rolls to the opening 14 from which it is discharged. After its discharge the coal may be conducted or conveyed to any point desired. The depth or width of the opening 14 may be varied by adjusting the plate 50 which is located upon the outer side of the front side 4 of the tank. In the position as illustrated in Fig. 1 of the drawing the lower edge of the said adjustable plate 50 occupies a position below the upper edge por-

tion of the opening 14. However, it will be understood that the said plate may be adjusted upwardly by means of the rotatable gear wheel 51 which is in engagement with a rack 52 the lower end portion of which is connected to the plate 50, and also that it may be adjusted downwardly.

After the coal has once reached a position over the plate 11, it will, in case it should start to move downwardly, lodge upon the upper side of the said plate and thereby probably be prevented from continuing its descending movement to an extent sufficient to permit it to be re-commingled with the impurities which may rest upon the portion 33 of the perforated plate 27.

The impurities, which are of greater specific gravity than the coal, instead of being lifted and carried upwardly by the force of the flow of water through the perforated portions of the plate 27, rest upon the latter, particularly the portion 33 thereof. As the impurities pile up upon the portion 33 they engage the rear side of the lower edge portion of the gate 55 which is pivoted by means of ears 56 to the opposite sides of the tank 1. The upper edge of the gate 55 extends into position adjoining the lower side of the plate 11 and when the said gate is opened, as indicated by the dash and dot lines in Fig. 1, its opening movement may be limited by the contact of the upper edge of the said gate with the inner side of the narrow flange 12. The said gate is provided with a weight 58 adjoining its lower edge the presence of which constitutes an additional weight which by the action of gravity tends to hold the gate 55 in the closed position shown in Fig. 1.

The slate and other impurities which are separated from the coal are discharged into a trough 60, the upper side of which is open as shown. The rear edge portion of the said trough is in alinement with and in adjoining relation to the lower front edge of the plate 27 and also in substantial alinement with the gate 55 when the latter is in the position shown in full lines in Fig. 1 of the drawing. The opposite edge of the trough is provided with an extension plate 61 which terminates in adjoining relation to the lower edge of the plate 10 and to the lower edge of the opening 14 and is seated against the front wall 4. The slate and other impurities which may have been separated from the coal are discharged into the trough 60 the bottom of which is inclined transversely of or across the apparatus, as best illustrated in Fig. 2, and discharges into a pipe 62 the lower end portion of which extends downwardly as indicated at 63 and is closed by means of a closing plate 64 or disk 64. The downwardly extending or depending portion 63 of the pipe is provided with openings 65 in the sides thereof a short distance above its lower end. For the purpose of controlling these openings I have provided

a valve 66 which is located within the depending portion 63 of the said pipe and is connected to and supported upon the upper end of a rod 67 which extends upwardly through 5 an opening 68 in the closing plate or disk 64. The lower end of the rod 67 is connected to the inner end of a lever 70 pivoted intermediate its ends to a bracket arm 71 depending downwardly and outwardly from the closing 10 plate or disk 64. The said lever 70 is provided upon its outer end with a weight 72 which is adjustable thereon as indicated. Gravity acting upon the weight 72 and upon the outer end portion of the lever 70 tends to cause upward movement of the valve 66 to close or 15 partially close the openings 65. The slate and other impurities which are discharged into the trough 60 travel therethrough and outwardly into the pipe 62 and descend upon 20 the valve 66. When the weight of these impurities is sufficient to cause the latter to descend in opposition to the action of gravity upon the weight 72 the ports 65 are opened and the impurities are discharged there- 25 through until the force exerted by the weight of the impurities above and which rest upon the valve 66 becomes less than the force exerted by the weight 72, whereupon the valve 66 is caused to move upwardly to again close 30 the ports 65. If the percentage of impurities in the mixture of coal and impurities is great the probabilities are that the valve 66 may be held almost continuously in open position; but if the percentage of impurities is very 35 small the said valves may be opened only at intervals.

In the operation of the apparatus the mixture of coal and impurities falls first upon the uppermost imperforate portion 75 of the 40 plate 27 from which it slides off onto the portion 31 where it is first subjected to the action of an upwardly flowing stream of water. The action of this stream may be to separate the coal from the impurities and carry the 45 same upwardly and forwardly over the plate 11 and also over the adjustable breast plate 5. If, however, a portion of the coal remains commingled with the impurities it may be separated or partially separated by the action 50 of the water flowing through the perforations in the upright portion 32 of the plate 27. The remaining and complete separation is effected by the water flowing through the perforations in the portion 33 of the plate. By the action 55 of these three portions or streams of flowing water complete cleansing and separation of the impurities from the coal are effected.

It is to be remembered that in the operation of the device the opening 14 for the 60 discharge of the coal must be properly restricted by the restricting plate 50 so as to prevent the water from flowing too freely from the compartment 15. Better results are achieved when a certain amount of water is 65 retained in the said compartment.

Having thus described my invention, what I claim and desire to secure by Letters Patent is:

1. An apparatus for washing coal, comprising a tank having a curved passageway 75 extending therethrough and also having a plate extending across said passageway, said plate being provided with perforated angularly related portions two of which are located in upwardly inclined spaced parallel planes and the other one of which extends in a very nearly vertical plane and unites the adjoining edges of the other two portions, the upper end of the wall of said passageway being curved and extended into contact with the upper perforated end of the said plate to form therewith a pocket below the level of the water in the tank. 80

2. An apparatus for washing coal, comprising a tank provided with a curved passageway 85 extending therethrough, the said passageway being divided into lower and upper compartments by a plate extending downwardly and transversely thereacross, the said plate having a plurality of portions 90 extending transversely of the apparatus and being angularly related to each other, one of the said portions adjoining the rear side of the said tank being imperforate and others of the said portions nearer the front side of the said passageway being provided with perforations, the uppermost and lowermost of the last named portions being in spaced substantially parallel planes and the intermediate portion connecting the adjoining edges of the two last named portions being located in a plane extending transversely of the said two parallel planes, and a curved plate located within said passageway adjoining a portion of the rear wall thereof and contacting at its upper edge with the upper edge of the uppermost of the last three named portions and contacting at its lower edge portion with the inner side of the rear wall of the said passageway, the said perforated portions operating to divide the water flowing through the said passageway into three streams which cooperate to effect separation of the coal and impurities, substantially as described. 100 105 110

3. Apparatus for washing coal, comprising a tank having a curved passageway leading from the bottom portion of the front wall thereof and extending rearwardly and upwardly, a plate extending from the rear wall of the said tank downwardly and transversely of the said passageway, the lower portion of the said plate comprising three angularly related portions which extend transversely of the said tank, which portions 120 are perforated, the lowermost and uppermost portions being located in inclined spaced planes which are substantially parallel with each other, and the intermediate of the said perforated portions being connected at its 125 130

opposite edges to the adjoining edges of the said upper and lower portions, and a curved plate located in the said passageway opposite the said lower perforated portion of the said plate, the upper edge portion of the said curved plate cooperating with the two uppermost of the said perforated portions to form a pocket below the level of the water in the tank from which pocket water is discharged in substantially vertical and horizontal directions, the streams thus produced co-operating with a stream formed by the passage of water through the perforations in the lowermost of the said portions, substantially as described.

4. An apparatus for washing coal, comprising a tank having a curved passageway extending therethrough and also having a plate extending across said passageway, said plate being provided with perforated angularly related portions two of which are located in upwardly inclined spaced parallel planes and the other one of which extends in a very nearly vertical plane and unites the adjoining edges of the other two portions, the upper end of the wall of the said passageway being curved and extended into contact with the upper perforated end of the said plate to form therewith a pocket, means for depositing a mixture of coal and impurities upon the uppermost portions of said plate, the coal and the impurities being separated by the action of water directed upwardly through the perforations formed in said plate and means for preventing the descent of coal downwardly in the said apparatus after it has arrived at a point in adjoining relation to its point of discharge.

5. Apparatus of the character described, comprising a tank having a curved passageway extending therethrough, said passageway having front and rear walls, a plate extending downwardly from the rear wall transversely of and across the said passageway, a portion of said plate having perforations therethrough, and a curved plate located in said passageway below the first named plate, with its lower edge portion resting upon the rear wall thereof, and its upper edge being located in co-operative relation to the upper edge of the perforated portion of the first named plate and co-operating with said first named plate to form a pocket below the level of the water in the tank, from which pocket water is discharged both longitudinally and transversely of the said curved passageway.

In testimony that I claim the foregoing as my invention, I have hereunto signed my name this 27th day of October, A. D. 1927.

CHARLES F. RICHARDS.
